UNITED STATES PATENT OFFICE.

JOSEPH H. COOPER, OF PITTSBURGH, PENNSYLVANIA.

DRIFTING DEVICE

1,245,442.

Specification of Letters Patent.

Patented Nov. 6, 1917.

Application filed February 9, 1916. Serial No. 77,170.

To all whom it may concern:

Be it known that I, JOSEPH H. COOPER, a citizen of the United States, residing at Pittsburgh, in the county of Allegheny and 5 State of Pennsylvania, have invented certain new and useful Improvements in Drifting Devices, of which the following is a specification.

The invention relates to means for supplying steam to locomotive cylinders when the locomotive is drifting, in order to break the vacuum which would otherwise be formed, and more important prevent the drying out of the walls of the cylinders and 10 the vaporization of the oil on such surfaces. The invention has for its principal objects the provision of a simple and reliable apparatus (1) which will act automatically to provide an adequate quantity of steam 15 when the throttle is closed and the engine is drifting and only at such times, and (2) which will proportion the quantity of steam supplied to the speed at which the engine is drifting. One embodiment of the invention is shown in the accompanying drawings, wherein—

Figure 1 is a diagrammatic plan view showing the general arrangement of the parts, and Fig. 2 is a section on an enlarged scale through the controlling valve mechanism.

The invention finds its principal use in connection with superheated steam with which the overheating of the cylinder is 35 greatest, and in the embodiment illustrated, comprises a supplemental saturated steam supply means provided with two controls, one of which is closed when the locomotive throttle is opened and opened when the 40 throttle is closed, and the other of which is closed when the engine is standing, but is opened by pressure accumulated in a reservoir from some point on the outlet side of the throttle, such reservoir being provided 45 with a bleed passage so that the pressure is exhausted within a given time. The reservoir is preferably charged by back pressure from the cylinders and this back pressure is preferably continued after the 50 throttle is closed so that the second controlling means is open while the engine is drifting.

Referring first to the general arrange-

ment, 1 is the boiler of the locomotive; 2, 2 are the engine cylinders carrying the pistons 3, 3; 4 is the main steam supply pipe controlled from the usual throttle valve 5 and provided with the branches 6, 6 leading into the steam chests of the cylinders; 7 is the casing of the valve mechanism for controlling the supplemental supply of steam, when the throttle is closed and the engine is drifting; 8 is the turret of the engine supplied with saturated steam from the steam dome by means of the pipe 9; 10 is the conduit for supplying saturated steam from the turret to the valve casing 7; 11 is the outlet pipe from the casing 7 provided with the branches 12, 12, and 13, 13, such branches being provided with the check valves 14 to 60 prevent a back-flow of pressure from the cylinders; 15 is a pipe leading from one of the branches 6 to the casing 7; and 16 is a pipe leading from one end of the right-hand cylinder 2 to the casing 7 and provided with a branch 17 leading to the other end of the cylinder, such pipes 16 and 17 both being provided with check valves 18 preventing any flow of steam into the cylinder.

The relation of the piping to the valve 80 casing 7 will be readily understood by reference to Fig. 2, wherein the ends of the various pipes are shown in dotted lines. Located in the upper portion of the casing 7, as indicated in Fig. 2, is the piston valve 85 19 adapted to govern the flow of steam through the ports 20, the valve being held in its open position as illustrated, by means of the spring 21. Below the piston valve 19 is a second piston valve 22 held in the position shown by means of the spring 23, the valve in such position closing the series of ports 24 leading into the cavity 25 surrounding the ports. The valve carries at its left hand end a piston head 26 whose outer end 90 is exposed to pressure from a reservoir 27. The pressure is supplied to the chamber 27 from the pipe 16 past the outwardly opening check valve 28 yielding held closed by the spring 29. A bleed passage 30 leading 100 from the reservoir to the cavity 31 is regulated by means of the stud 32 held in position of adjustment by means of the nut 33.

When the engine is standing and the throttle valve 5 is closed the valve parts 105 occupy the position indicated in Fig. 2, the

spring 21 holding the valve 19 in open position and the spring 23 holding the valve 22 in closed position. At this time steam pressure from the pipe 10 is admitted to the cavity 34, but is prevented from passing to the cavity 31 and the pipe 11 by the valve 22. If now the throttle valve 5 is opened to start the locomotive, steam from the main supply pipe 4 passes into the pipe 15 and thence into the cavity 35 at the left hand end of the piston 19, causing this valve to move to the right to closed position, thus preventing any flow of steam to the cavity 31 after the valve 22 is opened as hereinbefore set forth. The pressure in the cylinder 2 including the back pressure as the piston approaches the end of its stroke is transmitted through the pipe 16 to the cavity, beneath the check valve 28 (Fig. 2) and past such check valve into the reservoir 27, and when this pressure reaches a certain point the piston head 26 is forced to the right opening the valve 22. There is a continual loss of pressure through the bleed passage 30, but this is not sufficient to prevent the accumulation of the necessary pressure in the reservoir. With the locomotive running, therefore, and the throttle valve open, there is still no flow of steam from the pipe 10 to the pipe 11 since the valves 19 and 22 have interchanged their positions, the valve 19 being closed and the valve 22 open. The relative strength of the springs 21 and 23 is such that the valve 19 closes before the valve 22 opens. If now the throttle valve 5 is closed and the locomotive begins to drift, the condition arises in which the apparatus performs its function of supplying saturated steam from the pipe 10 to the ends of the cylinders. The closing of the throttle valve 5 cuts off the pressure in the pipe 4 and in the pipe 15 leading to the cavity 35 at the left hand end of the valve 19 (Fig. 2), so that as soon as the throttle valve is closed the valve 19 is moved by the spring 21 to open position, as shown in Fig. 2. At this time the valve 22 is also open due to the accumulated pressure in the reservoir 27 so that saturated steam is allowed to flow freely from the cavity 34 to the cavity 31 and thence through the pipes 11 and 12 to the ends of the cylinders. During the period of drifting, pressure is still supplied to the reservoir 27 because of the back pressure in the cylinder produced as the piston reaches the ends of its stroke. The piston head 26 and the valve 22 are therefore held to the right as the drifting continues. The position of the valve 22 during the drifting operation will depend upon the speed at which the locomotive is moving since the accumulation of pressure in the reservoir 27 will be proportional to the rate at which the back pressure is supplied from the cylinder. As the locomotive slows down and the valve 22

moves to the left, the amount of valve opening permitted by the valve 22 will be reduced, thus cutting down the supply of saturated steam to the cylinders, the amount of steam thus being made proportional to the speed of the locomotive. The release of pressure from the reservoir will be dependent upon the size of the bleed opening and this can be regulated to suit requirements by means of the stud 32. When the locomotive comes to a stop there is no longer any addition of pressure to the reservoir 27 and the accumulated pressure leaks out through the passage 30 so that the valve 22 entirely closes at this time if it has not closed before the complete stop. The parts are thus restored to the position of Fig. 2 the same as at the beginning of the cycle above described.

The check valves 13 are provided in order to prevent the steam from one side of the piston blowing to the other side through the pipe 12 and the check valves 18 prevent the back pressure which is accumulated at one end of the cylinder as the piston approaches such end from being dissipated into the other end of the cylinder instead of passing to the accumulating reservoir 27, and they further prevent the blowing of steam from one end of the cylinder to the other as specified with respect to the check valves 13. The bleed passage 36, leading from the cavity in front of the valve 22 (Fig. 2) prevents the accumulation of pressure in such cavity due to leakage past the valve. It will be understood by those skilled in the art that the invention is intended primarily for use in connection with superheated steam, and that superheated steam might be supplied to the cylinders during the drifting operation although for the sake of simplicity in illustration no attempt has been made to show a superheater.

I have illustrated only one embodiment of my invention but it will be understood that the broad invention as defined in the claims is capable of use in various modified structures. The pressure for the reservoir is preferably secured from the cylinders and from back pressure during the drifting operation, but it will be understood that this pressure might be secured in other ways and that the invention contemplates broadly the use of a pressure reservoir in which pressure accumulates from the outlet side of the throttle and from which a gradual release of pressure occurs to permit the closing of a cut-off valve for the saturated steam. The use of the back pressure from the cylinders for providing the accumulated pressure is preferred because the pressure is thus maintained as long as the engine is drifting at a predetermined speed which would not be the case if the reservoir were merely filled before the drifting operation.

and no additional supply was added during the drifting and proportional to the speed of drifting.

What I claim is:

5. 1. The combination with a locomotive, of a drifting device comprising a conduit leading from the boiler for supplying steam to a locomotive cylinder, closure means in the conduit moved to closed position by the 10 opening of the locomotive throttle, and other closure means in the conduit moved to open position by cylinder back pressure. 70
15. 2. The combination with a locomotive, of a drifting device comprising a conduit leading from the boiler for supplying steam to a locomotive cylinder, closure means in the conduit, means whereby the closure means is opened when the locomotive throttle is closed and closed when the throttle is opened, and 20 other closure means in the conduit moved to open position by cylinder back pressure. 80
25. 3. The combination with a locomotive, of a drifting device comprising a conduit leading from the boiler for supplying steam to a locomotive cylinder, closure means in the conduit, means whereby the closure means is opened when the locomotive throttle is closed and closed when the throttle is opened, and other closure means in the conduit moved to 30 closed position by cylinder back pressure when the locomotive is running. 90
35. 4. The combination with a locomotive, of a drifting device comprising a conduit leading from the boiler for supplying steam to a locomotive cylinder, closure means in the conduit moved to closed position by the opening of the locomotive throttle, and 40 other closure means in the conduit yielding- 100
45. 5. The combination with a locomotive, of a drifting device comprising a conduit leading from the boiler for supplying steam to a locomotive cylinder, closure means in the conduit, means whereby the closure means is opened when the locomotive throttle is closed and closed when the throttle is opened, and other closure means in the conduit yielding- 110
50. 6. The combination with a locomotive, of a drifting device comprising a conduit leading from the boiler for supplying steam to a locomotive cylinder, closure means in the conduit yielding held open when the locomotive throttle is closed but moved to closed position by 55 steam pressure on the outlet side of the 115
60. 7. The combination with a locomotive, having a supplemental steam supply means for the locomotive cylinders and controlling means therefor closed automatically when the throttle valve of the locomotive is opened and opened when such valve is closed, of other controlling means for the said steam supply means opened by locomotive cylinder back pressure. 120
65. 8. The combination with a locomotive having a supplemental steam supply means for the locomotive cylinders and controlling means therefor yielding held open, and closed automatically by steam pressure from the outlet side of the locomotive throttle valve, of other controlling means for the said steam supply means yielding held closed but adapted to be opened by locomotive cylinder back pressure. 125
70. 9. The combination with a locomotive having a supplemental steam supply means for the locomotive cylinders and controlling means therefor closed automatically when the throttle valve of the locomotive is opened and opened when such valve is closed, of other controlling means for the said steam supply means opened by locomotive cylinder back pressure, a reservoir in which the back pressure is accumulated, and a bleed passage leading from the reservoir. 130
75. 10. The combination with a locomotive having a supplemental steam supply means for the locomotive cylinders and controlling means therefor yielding held open, and closed automatically by steam pressure from the outlet side of the locomotive throttle valve, of other controlling means for the said steam supply means yielding held closed but adapted to be opened by locomotive cylinder back pressure, a reservoir in which the back pressure is accumulated, and 80
85. 11. The combination with a locomotive having a supplemental steam supply means for the locomotive cylinders and controlling means therefor yielding held open, and closed automatically by steam pressure from the outlet side of the locomotive throttle valve, of other controlling means for the said steam supply means yielding held closed but adapted to be opened by locomotive cylinder back pressure, a reservoir in which the back pressure is accumulated, a check valve for preventing a back flow from the reservoir, and means for permitting a gradual release of the accumulated pressure. 120
90. 12. The combination with a locomotive, 130

having a supplemental steam supply means for the locomotive cylinders and controlling means therefor closed automatically when the throttle valve of the locomotive is opened 5 and opened when such valve is closed, of other controlling means for the said steam supply means opened by locomotive cylinder back pressure, the said means being arranged to give an opening which is proportional to 10 the accumulated back pressure.

13. The combination with a locomotive having a supplemental steam supply means for the locomotive cylinders and controlling means therefor closed automatically when 15 the throttle valve of the locomotive is opened and opened when such valve is closed, of other controlling means for the said steam supply means opened by locomotive cylinder back pressure, a reservoir in which the back 20 pressure is accumulated, and a bleed passage leading from the reservoir, the said controlling means governed by back pressure having a graduated opening so that the amount of opening and the quantity of steam passing 25 said means is proportional to the accumulation of back pressure in the reservoir and proportional to the speed of the locomotive.

14. The combination with a locomotive 30 having a supplemental steam supply means for the locomotive cylinders and controlling means therefor open when the locomotive is drifting, of other controlling means for the said steam supply means opened by locomotive cylinder back pressure.

15. The combination with a locomotive having a supplemental steam supply means for the locomotive cylinders and controlling means therefor open when the locomotive is 35 drifting, of a valve for said steam supply means, a spring for yieldingly closing the valve, and means whereby the valve is held open by cylinder back pressure.

16. The combination with a locomotive 40 having a supplemental steam supply means for the locomotive cylinders and controlling means therefor open when the locomotive is drifting, of a valve for said steam supply means having a graduated opening, a spring 45 for yieldingly closing the valve, and means communicating with a locomotive cylinder

whereby cylinder back pressure is accumulated and applied to holding the valve open a distance proportional to the rate at which the back pressure is accumulated. 55

17. The combination with a locomotive having a supplemental steam supply means for the locomotive cylinders and controlling means therefor open when the locomotive is drifting, of other controlling means for the 60 said steam supply means opened by locomotive cylinder back pressure, a reservoir in which the back pressure is accumulated, and means for permitting a gradual release of the accumulated pressure. 65

18. The combination with a locomotive having a supplemental steam supply means for the locomotive cylinders and controlling means therefor open when the locomotive is drifting, of other controlling means for the 70 said steam supply means opened by locomotive cylinder back pressure, a reservoir in which the back pressure is accumulated, a check valve for preventing a back flow from the reservoir, and means for permitting a 75 gradual release of the accumulated pressure.

19. The combination with a locomotive having a supplemental steam supply means for the locomotive cylinders and controlling means therefor open when the locomotive is 80 drifting, of a valve for said steam supply means, having a graduated opening, a spring for yieldingly closing the valve, means whereby cylinder back pressure is accumulated and applied to hold the valve open a 85 distance proportional to the rate at which the back pressure is accumulated, and means whereby the accumulated back pressure is gradually released.

20. The combination with a locomotive 90 having a supplemental steam supply means and controlling means therefor yieldingly held open, and closed by steam pressure from the outlet side of the locomotive throttle, of other controlling means yieldingly held 95 closed, a reservoir to which steam pressure is supplied when the locomotive throttle is open and from which pressure is supplied to open said other controlling means, and means for permitting the gradual release of 100 the pressure in the reservoir.

J. H. COOPER.
